ROADSIDE FARMERS' MARKET EDUCATIONAL TOY

Geraline Rodio, North Egg Harbor Road,
Hammonton, N.J. 08037

Filed Sept. 27, 1968, Ser. No. 13,752

Term of patent 14 years

Int. Cl. D25—04; D21—02
U.S. Cl. D34—15

FIG. 1.

FIG. 2.

FIG. 3.

FIG. 4.

FIG. 5.

FIG. 6.

FIG. 1 is a front perspective view of a roadside farmers' market educational toy embodying my new design;

FIG. 2 is a front elevation thereof;

FIG. 3 is a rear elevation;

FIG. 4 is a side elevation on a reduced scale, as viewed from the right side of FIG. 2;

FIG. 5 is a side elevation on a reduced scale, as viewed from the left side of FIG. 2; and

FIG. 6 is a top plan view, also on a reduced scale.

I claim:

The ornamental design for a roadside farmers' market educational toy, substantially as shown.
